T. E. ROGERS

FRONT FENDER BRACE

Filed June 5, 1924

Inventor

T. E. Rogers

By

Lacy & Hailey, Attorneys

UNITED STATES PATENT OFFICE.

THEODORE E. ROGERS, OF ZAP, NORTH DAKOTA.

FRONT-FENDER BRACE.

Application filed June 5, 1924. Serial No. 718,070.

To all whom it may concern:

Be it known that I, THEODORE E. ROGERS, a citizen of the United States, residing at Zap, in the county of Mercer and State of North Dakota, have invented certain new and useful Improvements in Front-Fender Braces, of which the following is a specification.

This invention relates to an improved front fender brace for Ford motor cars and seeks, among other objects, to provide a device of this character which will prevent sagging of the front fenders, which will minimize vibration of the front fenders and associated parts, which may be adjusted to take up any looseness in the mounting of the front fender brackets, which will impart rigidity to the mounting of the headlights, and which will tend to prevent spreading of the frame bars of the chassis at the forward end thereof and consequently overcome injury to the radiator now brought about by said cause.

And the invention further seeks to provide a brace which may be applied without the necessity for any structural change whatever in the vehicle.

Other and incidental objects will appear hereinafter.

In the drawing:

Figure 1 is a front elevation showing a conventional Ford vehicle equipped with my improved brace, one of the front fender aprons being partially broken away and illustrated in section, and

Figure 2 is a detail perspective view of one of the brace links employed.

As is well known, the front fenders of a Ford vehicle very often sag while the front fender brackets not infrequently become loose with resultant rattling. The present invention, therefore, seeks to provide a simple and efficient device to overcome these troubles as well as a device which will serve to prevent vibration of the headlights of the vehicle and also brace the frame of the vehicle chassis at its forward end so that the frame bars will be prevented from spreading under the weight of the engine with consequent injury to the engine radiator. In Figure 1 of the drawing, I have shown my improved device in connection with a conventional Ford vehicle wherein the front fenders are indicated at 10, the fender brackets at 11, and the headlights

and their supporting posts at 12 and 13 respectively. As is well known, the brackets 11 are riveted at their lower ends to the side bars of the vehicle chassis and are provided near their lower extremities with eyes 60 14 which receive reduced studs 15 at the lower ends of the posts 13 and screwed upon said studs are nuts 16 connecting the posts with the brackets.

Coming now more particularly to the subject of the present invention, I employ a pair of anchoring links 17. These links are each preferably formed from a length of suitable resilient material such, for instance, as a steel rod which is flattened at 70 one end to form a terminal lug 18 and bent at its opposite end to provide a rearwardly directed loop or sleeve 19, while near the lug 18, the rod is further bent to define a forwardly directed eye 20. In applying the 76 links, the fenders are detached from the outer ends of the brackets 11, when the loops 19 are slipped over the brackets and the links moved downwardly along the brackets to the approximate position shown in Figure 1, the fenders being subsequently, of course, again secured to the brackets. The nuts 16 are then removed, when the lugs 18 of the links are slipped over the studs 15 and the nuts applied and tightened for rigidly 85 connecting the links at their lower ends with the posts 13 of the headlights.

In conjunction with the links 17, I employ a cross rod 21 which is slipped through the eyes 20 of the links, and screwed upon 90 the rod to abut the eyes at their inner sides are nuts 22 while similar nuts 23 are screwed upon the rod to abut the eyes at their outer sides. Thus, as will be seen, by loosening the nuts 22, the nuts 23 may be 95 adjusted for drawing the links toward each other and exerting an upward strain on the brackets 11 and, if necessary, swinging the brackets upwardly and lifting the fenders, when the nuts 22 may be tightened for securing the parts in adjusted position. The loops 19 of the links are, of course, provided to accommodate movement of the outer ends of the links along the brackets 11 when the brackets are thus swung upwardly and, as 100 will be appreciated, after the brace has been tightened, said brace will serve to reinforce and support the fender brackets under the weight of the fenders and not only prevent sagging of the fenders but also prevent vi- 110

bration thereof as well as vibration of the fender brackets. Furthermore, the brace will also overcome any prior looseness in the mounting of the posts 13 and will hold the posts rigid to prevent vibration of the headlights as well as tend to prevent spreading of the frame bars of the vehicle chassis at their forward ends and consequently avoid injury to the engine radiator from such cause. Near its ends, the cross rod is offset so that, in applying the device to different vehicles, the rod may, after having been initially inserted through the eyes 20 of the links, be rotatably positioned to compensate for variation in the distance between the lower margins of the fender aprons and the brackets 11 so that the rod may not interfere with the fenders, the starting crank or any part of the car.

Having thus described the invention, what I claim is:

1. The combination with a motor vehicle having front fender brackets, and headlight supporting posts mounted on said brackets, of means slidably engaged at their upper ends with the brackets and fixed thereto at their lower ends by said posts, and a cross rod extending between said means supporting the brackets against downward stress.

2. The combination with a motor vehicle having front fender brackets, and headlight supporting posts mounted on said brackets, of a pair of links slidably engaged at their upper ends with the brackets and secured at their lower ends to said posts, and a cross rod extending between the links

and engaged with the links at points between the ends thereof.

3. The combination with a motor vehicle 40 having front fender brackets, and headlight supporting posts mounted on said brackets, of a pair of links slidably engaged at their upper ends with the brackets and secured at their lower ends to said posts, the links being provided medially with eyes, and a cross rod extending through said eyes 45 connecting the links with each other and supporting the brackets against downward stress. 50

4. The combination with a motor vehicle having front fender brackets, and headlight supporting posts mounted on said brackets, of a pair of links provided at their upper ends with loops slidably receiving the brackets therethrough and at their lower ends with lugs secured upon the lower ends 55 of said posts, the brackets being provided medially with eyes, and a cross rod engaged with said eyes connecting the links with each other. 60

5. A front fender brace for motor vehicles including a pair of links provided at their upper ends with loops to receive fender brackets therethrough and at their lower ends with apertured lugs for engagement with headlight posts carried by said brackets, the links being formed medially 65 with eyes, a cross rod to extend between the links through said eyes, and means upon the 70 rod connecting the rod with said links.

In testimony whereof I affix my signature.

THEODORE E. ROGERS. [L.S.]
